FIRE EXTINGUISHER

Arthur Rodgers, Northbrook, Ill., assignor to Fire Guard Corporation, a corporation of Illinois

Filed Nov. 19, 1964, Ser. No. 82,692

Term of patent 14 years

(Cl. D16—2)

FIG.1.

FIG.2.

FIG.3.

FIG.4.

FIG.5.

I claim:

The ornamental design for a fire extinguisher, substantially as shown.
